William C. Lehman, Cannelton, Ind., assignor to
The Lehman Company of America, Inc., Cannelton, Ind., a corporation of Indiana

Application August 24, 1934, Serial No. 741,210

3 Claims. (Cl. 45—70)

The present invention relates to improvements in desks.

The primary object of the invention is the provision of a desk which has the conveniences of the pigeonhole type of desk but is readily converted into a flat top desk.

In the accompanying drawings there is illustrated two preferred embodiments of the invention. It is to be understood, however, that these 10 embodiments are given for purposes of exemplification only and are not to be construed as unnecessarily limiting the scope of the protection sought and defined by the appended claims.

Referring to the drawings:

15. Fig. 1 is a view in elevation showing a desk with the back portion containing the pigeonholes in raised position;

Fig. 2 is a view in elevation showing a desk with the back portion containing the pigeonholes 20 in closed position so that the desk has the appearance of a flat top desk;

Fig. 3 is a detailed view in section with portions broken away and portions shown in dotted lines to illustrate one form of mechanism for 25 operating the back portion of the desk;

Fig. 4 is a sectional view showing the same form of mechanism as disclosed in Fig. 3, Fig. 3 being taken on the line 3—3 of Fig. 4;

Fig. 5 is a detailed sectional view of an oil 30 piston dashpot used in conjunction with the raising and lowering mechanism;

Fig. 6 is a view showing the guide means for the back portion of a desk;

Fig. 7 is a view showing a modified form of 35 mechanism employing counterweights for raising and lowering the back portion of a desk; and

Fig. 8 is a section taken on the line 8—8 of Fig. 7.

Referring first to the construction shown in 40 Figs. 1 to 6, inclusive, it will be observed that the desk proper, which is indicated by the reference numeral 11, has a back portion 12 containing a plurality of pigeonholes, as shown in Fig. 1. The back portion 12 is provided at each end with 45 downwardly extending members 12^a and stops 12^b. Attached to the members 12^a are metal guide strips 13 that ride in metal grooves 14 secured in the outer side walls of the desk. The back portion of the top of the desk is, therefore, 50 slideable upwardly and downwardly so that it may assume the positions shown respectively in Figs. 1 and 2.

It is preferable to make the slideable back portion as a separate insert that fits within the 55 outer walls of the desk, as is apparent from Fig.

6, although it can be constructed with the back portion of the desk serving as one of the walls.

The balance of the desk, as shown in the drawings, is of standard construction. Obviously, however, the arrangement of the main portion of 5 the desk is not of the essence of the invention.

To operate the sliding back portion of the desk 12 a spring and oil piston mechanism, shown in detail in Figs. 3 and 4, is provided. The spring 15 is fastened at its upper end 16 by means of a 10 suitable fastening member 17 to a fixed portion of the body of the desk. Extending downwardly and rigidly secured to the top is a frame member 18, to the bottom 19 of which is secured the bottom of the spring 15. An oil plunger or dashpot 20 is provided, the piston rod 21 of which is secured at its upper end 22 to a fixed portion of the body of the desk and the cylinder 23 is secured at the bottom 24 by suitable fastening means to the frame member 18. 20

A stop member 25 is provided to engage openings 26 in the front wall 27 of the frame member 18. The stop member 25 is provided with a handle member 28 and a coil spring 29 which abuts against the block 30 and a collar 31, the latter 25 being secured to the stop member 25.

In the operation of the mechanism thus far identified by reference numerals, the handle member 28 is pulled outwardly to compress the coil spring 29 and remove the stop member from 30 the lower opening 26 of the mechanism shown in Fig. 3. The sliding top portion of the desk may now be depressed and upon being depressed the coil spring 29 will be expanded and the piston 21 will move upwardly in the cylinder 23. 35 When the top portion 12 has reached the final position so that it is flush with the top of the remainder of the desk the stop 25 will engage the top opening 26 and hold the top member 12 in closed position. In this position the spring, 40 plunger and frame member 18 will be in the position shown in dotted lines in Fig. 2.

Referring to Fig. 4 it will be observed that in this view the top portion 12 is in closed position and the spring 15 is fully expanded. The details 45 of the oil piston or dashpot are shown in Fig. 5. This dashpot is of standard construction, the cylinder being filled with oil and the piston being provided with a channel 32 through which the oil may flow when the piston is moved back 50 and forth although, obviously, the channel is sufficiently small to retard the movement of the piston and, consequently, the top of the desk when it is manipulated.

To raise the top portion 12, the handle 28 is 55

pulled outwardly to remove the stop 25 from the upper opening 26. The spring 15, being in an expanded position, will exert force through the frame member 18 to the top of the desk and raise the top of the desk. The presence of the dashpot retards the action of the spring so that the top moves up slowly and gently and reaches its final position with a smooth and easy action.

The spring and dashpot mechanism is located at the center of the desk so that the device operates evenly and the slidable portion of the top does not bind.

Referring to the construction shown in Figs. 7 and 8, it will be observed that in this modified embodiment of the invention a counterweight is employed in lieu of the spring and dashpot mechanism. Projecting downwardly from in back of the desk will be found the member 36 which is provided with openings 37 to receive the stop member 38, the latter being provided with a handle 39. A cross member 40 is fixedly secured to a stationary portion of the desk, preferably the back thereof, at a point below the final resting place of the top section 12 when it is in lowered position. Depending from the member 40 is a rope 41 which passes downwardly around a pulley 42. The pulley 42 is mounted on a member 43 which extends down from and is integral with the top member 12. After passing around the pulley 42 the rope 41 passes around the pulley 44 which pulley is secured to the member 40. The rope then extends across the back of the desk around the pulley 45 which is likewise secured to the member 40 and thence around the pulley 46 which is secured to the top of the weight 47. The rope then passes around the pulley 48, this pulley also being secured to the member 40 and thence downwardly to the pulley 50, the latter pulley being fixed to the member 51, which member, like the member 43, is also secured to the top of the desk. Thence the rope extends upwardly to the member 40 and is fastened thereto. The weight 47 and the pulleys 45 and 48 may be located behind the drawers in the desk so that they are not conspicuous.

In the operation of this form of device, when the desk is lowered, as shown in full lines in Fig. 7, the weight 47 is raised and the stop 38 fits in the upper hole 37. When the stop 38 is removed from the hole 37 by means of the handle 39 the weight through the rope and pulley system exerts an upward force on the members 43 and 51, raising the top of the desk to the position shown in dotted lines in Figs. 7 and 8. Obviously, the stop 38 then fits in the lower hole 37 and the movable portion 12 at the top of the desk is rigidly held in place. Removing the stop 38 from the lower hole 37 and pressing down on the top portion 12 of the desk will force it into flush position and the weight, through the rope and pulley mechanism, will be raised to the position shown in full lines in Figs. 7 and 8.

The invention is particularly useful in desks

of various kinds and types wherein it is desired to have the advantage of pigeonholes and at the same time avoid their unsightly appearance except when the desk is in use. By utilizing the invention it is possible to quickly clear the desk and lower the back member and thus give it a neat appearance for the purpose of receiving visitors in business offices and the like. This is also a desirable and advantageous feature for a desk constructed for use in the home.

The invention has been embodied in children's desks and is found to have an appeal to the child because of its mechanical nature and also to the mother because it may be quickly put in order.

If the top and guide mechanism is carefully constructed, when the portion 12 is closed the desk has a finished appearance and the small crack between the body portion of the desk and the portion 12 is barely noticeable.

I claim:

1. In a desk the combination of a body portion, a fixed top portion and a vertically slidable top portion, means for raising said slidable top portion comprising a spring secured to the body portion of said desk and to said top portion, said spring being under tension when said top portion is in lowered position, a dashpot cooperatively associated with said spring to retard the return of energy therefrom and means for securing said top portion in lowered position.

2. In a desk the combination of a body portion, a top, a portion of said top being slidable vertically, said top portion being provided with depending guide members that interfit in guideways in said body portion, a spring member secured at one end to said body portion, a member depending from said vertically slidable top portion and having the other end of said spring attached thereto in such manner as to place said spring under tension when said top portion is in lowered position, stop means associated with said vertically slidable portion of said top to fix the same in predetermined positions and means for retarding the action of said spring.

3. In a desk the combination of a body portion, a top, a portion of said top being slidable vertically, said top portion having depending members spaced from the side walls of said body portion, wear-resisting guide members mounted in said side walls, complementary wear-resisting guide members mounted in said depending members, said guide members maintaining a spaced relationship between said depending members and said side walls, means for exerting an upward pressure on said top portion when the same is in lowered position which upon release thereof will force said top portion upwardly and which upon downward pressure on said top portion will store energy to raise the same, and releasable means for securing said top portion in either raised or lowered position.

WILLIAM C. LEHMAN.
